UNITED STATES PATENT OFFICE.

CHARLES HENRY STENBERG, OF ELLSWORTH, IOWA.

THERMOSTATIC REGULATOR.

1,074,578.

Specification of Letters Patent. Patented Sept. 30, 1913.

Application filed September 27, 1912. Serial No. 722,758.

To all whom it may concern:

Be it known that I, CHARLES HENRY STENBERG, a citizen of the United States, residing at Ellsworth, in the county of 5 Hamilton and State of Iowa, have invented a new and useful Thermostatic Regulator, of which the following is a specification.

The object of my invention is to provide a thermostatic regulator of simple and inexpensive construction arranged and constructed to control the inflow of heated air to an incubator or the like.

A further object is to provide such a device provided with means whereby the inflow of hot air is automatically regulated by the change in temperature of the air surrounding the incubator or the like as well as by the change of temperature within the incubator.

More particularly it is my object to provide means within and without an incubator or the like for regulating the temperature within the incubator which means are arranged to coact with each other for controlling the inflow of warm air to the interior of the incubator.

My invention consists in certain details in the construction, arrangement and combination of the various parts of the device, whereby the objects contemplated are attained, as hereinafter set forth, pointed out in my claims and illustrated in the accompanying drawings, in which—

Figure 1 shows a vertical, sectional view through a portion of an incubator equipped with a thermostatic regulator embodying my invention. Fig. 2 shows a detail view in section of the thermostatic disk outside the incubator, and part of the mechanism adjacent thereto. Fig. 3 shows a detail sectional view of mechanism for mounting the rod which extends into the incubator to the thermostatic disk therein. Fig. 4 shows a detail section view of the operation of the rod 20.

In the accompanying drawings I have used the reference numeral 10 to indicate the walls or frame of an incubator which may be of heat insulating construction. Mounted within the incubator and spaced apart from the bottom thereof is an egg tray 11. The incubator may be supported upon the legs 12 if desired. Secured to the frame is a bracket 13 upon which rests an ordinary lamp 14 or other suitable source of heat. The chimney 15 of the lamp extends into a

cylinder 16 which is open at its upper end. Communicating with the cylinder 16 is a warm air conducting tube 17 which extends into the incubator preferably above the egg tray 11 and is open at its inner end for the purpose of discharging warm air within the incubator.

The parts heretofore described are of ordinary construction and of themselves form no part of my present invention.

Mounted on the top of the incubator frame 10 is an upwardly extending bracket 18 the upper end of which is preferably bifurcated thereby forming two arms 19. 70 Pivoted between the upper ends of the arms 19 is a rod 20. Pivoted to one end of the rod 20 is a downwardly extending rod 21 to the lower end of which is secured a cap or cover 22 designed in one position of its movement 75 to entirely close the upper end of the cylinder 16. Slidably mounted on the other end of the arm 20 is a weight 23 which may be secured in any position of its movement on the rod 20 by means of a set screw 24. 80 Mounted above the incubator is a lever arm 26 which extends between the arms 19. Mounted in one end of the lever arm 26 is a vertical screw 27, the lower end of which is contracted to a comparatively sharp point 85 and has approximately the form of an inverted cone. I have provided in the lever arm 26 a plurality of openings 26^a for mounting the screw 27 in different positions in the lever arm 26. 90

Mounted on the top of the incubator is a base or block 28 having at its upper surface a socket or vertical opening. Received in the socket in the block is a downwardly extending lug 29 on a thermostatic disk 30 of 95 ordinary construction. The lug 29 is vertically adjustable within the socket in the block 28 and may be secured in any position of its sliding movement by means of a set screw 31, mounted in the block 28. On the upper side of the disk 30 is a block or lug 30^a in the upper surface of which is a cavity shown by the dotted lines in Fig. 2. The pointed lower end of the screw 27 is received in the cavity in the block or lug 30 105 as shown by the dotted lines in Fig. 2. Thus it will be seen that one end of the lever arm 26 is supported by the disk 30.

Mounted on the upper side of the lever arm 26 is a block 32. The distance between 110 the block 32 and the end of the arm 26 which carries the screw 27 is preferably greater

than the distance between said block 32 and the other end of the arm 26. The block 32 is mounted on the lever arm 26 by means of screws 33. It will then be seen that the 5 position of the block 32 on the lever arm 26 may be varied as desired. In this connection it is stated that the bracket 19 has at its lower end a laterally extending flange 19^a which rests on the top of the incubator and 10 is secured thereto by means of screws 19^b so that said bracket may be secured to the incubator at different points for purposes of adjustment. Mounted in the rod 20 above the block 32 is a screw 34, the lower end of 15 which is received in a socket in the block 32 as shown by the dotted lines in Fig. 1. On the lower surface of the lever arm 26 near the end opposite the screw 27 I have mounted bearings 35 by means of screws 36, and in 20 the bearings 35 is rotatably mounted a round rod 37. Secured to the rod 37 between the bearings 35 is a downwardly extending rod 38. It will thus be seen that the rod 38 is 25 pivotally mounted on the lever arm 26 to move in a vertical plane. In the top of the incubator I provide an elongated opening 39. Above the opening 39 is a plate 40 having an elongated opening which registers with the opening 39. The rod 38 extends 30 downwardly through the plate 40 and the opening 39 to a position above the egg tray. The opening 39 and the opening in the plate 40 are of sufficient size to permit some play of the rod 38 when the lever arm 26 35 is moved up or down.

Mounted within the incubator is a bracket 39^a secured to which is a base or block 40 similar in construction to the base or block 28. A thermostatic disk 41 is adjustably 40 mounted in the block 40 in the same way that the disk 30 is mounted in the block 28. On the upper surface of the disk 41 is a lug or block 42 similar in construction to the block or lug 30^a having at its upper surface 45 a cavity in which is received the lower end of the rod 38. It will therefore be seen that the ends of the lever arm 27 is supported by the disk 41 and 30.

I will now describe the practical operation 50 of my improved thermostatic regulator. Assuming that the parts are installed in position as heretofore described, the temperature within the incubator may be very accurately regulated by means of my device. Assuming 55 that the lamp 14 is lighted for heating the air in the cylinder 16, the parts are adjusted so that when the disks 30 and 41 are contracted and in their normal position, the cover plate 22 will close the upper end of the 60 cylinder 16 and cause the heated air therein to be discharged through the tube 17 into the interior of the incubator. When a certain predetermined heat has been reached within the incubator, the disk 41 will expand there- 65 by raising the lever arm 26 and raising the

rod 20. The cover plate 22 will thus be raised above the cylinder 16 and the heated air in the cylinder will be permitted to pass out of the top thereof. When the air within the incubator cools, 70 the disk 41 will contract and the cover plate 22 will be thereby lowered and more warm air will be delivered to the incubator. It is a well known fact that the air in the bottom of the incubator and in the top there- 75 of varies considerably in temperature whenever the air outside the incubator is considerably higher or lower than the temperature of the air within the incubator. It is therefore desirable that the discharge of warm air into the incubator be regulated to some extent to correspond to changes in the temperature of the air outside the incubator. For effecting this regulation I have provided the thermostatic disk 30 and the parts 80 connected therewith. It will be readily seen that the parts may be adjusted by means of the screws in the blocks 40 and 31 and by varying the position of the bearings 35 and the block 32 and the screw 34 to meet all 85 ordinary variations in temperature. In this connection it is noted that I have provided in the rod 20, openings similar to the openings 26^a in the lever arm 26 in which the screws 34 may be mounted in different positions. By selectively mounting the screw 27 in different openings 26^a or selectively mounting the screw 34 in different openings 20^a, I am able to vary the effect of the disks 90 with relation to each other.

The advantages of my improved thermostatic regulator are numerous. I am able to regulate the internal temperature directly and also to regulate it according to changes in the temperature outside the incubator by 95 means of the adjustment features heretofore described. I am able to make adjustments to meet practically all conditions.

I claim as my invention.

1. In a device of the class described, an incubator frame, a rod pivotally mounted above same, a lever arm operatively and adjustably connected therewith, a disk mounted outside said frame operatively connected with said arm near one end thereof, a thermostatic disk mounted within said frame operatively connected with the other end of said arm, one of said disks being adjustably mounted with relation to said arm.
2. In a device of the class described, an incubator frame, a rod pivotally supported above said incubator frame, a lever arm above said incubator frame, means for operatively and adjustably connecting said rod and arm, said rod, a thermostatic disk adjustably mounted within said incubator frame, a rod pivotally mounted on said lever arm near one end thereof and extending through the top of said incubator frame to the top of said thermostatic disk, a thermo-

- static disk adjustably mounted on the outside of said incubator frame and adjustable for operatively connecting said second disk with said arm, whereby the contraction 5 or expansion of said last named thermostatic disk imparts movement to said lever arm.
3. In a device of the class described, an incubator body, a rod pivotally supported on said incubator frame, a lever arm above 10 said incubator body, adjustable means whereby the upward movement of said lever arm raises said first described rod, said first described rod being so mounted that it is lowered by its own weight when said 15 lever arm is lowered, a thermostatic disk mounted within said incubator frame, a rod pivotally mounted on said lever arm and extending downwardly through the top of said incubator frame and resting upon said 20 thermostatic disk, a thermostatic disk outside the incubator frame, operatively connected with said lever arm, said last named disk being longitudinally adjustable with relation to said arm.
- 25 4. In a device of the class described, an incubator frame, a receptacle adjacent thereto, means for heating the air in said receptacle, means for conveying heated air from said receptacle through the interior of 30 said frame, said receptacle being open at its upper end, a rod pivotally supported on said incubator frame, a cover device pivotally mounted on said rod and designed in one position of the movement thereof to 35 close the upper end of said receptacle, a lever arm above said incubator frame, means whereby the upward movement of said lever arm raises said first described rod, first described rod being so mounted that it is lowered by its own weight when said lever arm 40 is lowered, a thermostatic disk mounted within said incubator frame, a rod pivotally mounted on said lever arm near one end and extending downwardly through the top of 45 said incubator frame and resting upon said thermostatic disk, a thermostatic disk outside the incubator frame below the other end of said lever arm, means for vertically adjusting said last named disk, and means 50 whereby the expansion of said last named disk raises said lever arm.
5. In a device of the class described, an incubator frame, a receptacle adjacent thereto, means for heating the air in said receptacle, means for conveying heated air from 55 said receptacle through the interior of said
- frame, said receptacle being open at its upper end, a rod pivotally supported on said incubator frame, a cover device pivotally mounted on said rod and designed in one 60 position of the movement thereof to close the upper end of said receptacle, a lever arm above said incubator frame, means whereby the upward movement of said lever arm raises said first described rod, said first described rod being so mounted that it is lowered by its own weight when said lever arm is lowered, a thermostatic disk mounted within said incubator frame, means for adjusting said disk, a rod pivotally mounted 65 on said lever arm and extending downwardly through the top of said incubator frame and resting upon said thermostatic disk, a thermostatic disk outside the incubator frame below the free end of said lever 70 arm, and means whereby the expansion of said last named disk raises said lever arm.
6. In a device of the class described, an incubator frame, a receptacle adjacent thereto, means for heating the air in said receptacle, means for conveying heated air from 75 said receptacle through the interior of said frame, said receptacle being open at its upper end, a rod pivotally supported on said incubator frame, a cover device pivotally 80 mounted on said rod and designed in one position of the movement thereof to close the upper end of said receptacle, a lever arm above said incubator frame, means whereby the upward movement of said lever arm 85 raises said first described rod, said first described rod being so mounted that it is lowered by its own weight when said lever arm is lowered, a thermostatic disk mounted within said incubator frame, a rod pivotally 90 mounted on said lever arm and extending downwardly to the top of said incubator frame and resting upon said thermostatic disk, a thermostatic disk outside the incubator frame below the free end of said lever 95 arm, and means whereby the expansion of said last named disk raises said lever arm, and means for adjusting said last named disk, and said last described means longitudinally with relation to said lever 100 arm.
